ABSTRACT OF THE DISCLOSURE

A tool for cleaning the annular gasket-seating groove in a cylindrical opening in an air coupling member, with the tool having a recessed body with a cylindrical front pilot part and a rear handle part, a wire brush assembly guided for movement in the body recess and including a wire brush projecting radially outwardly from the pilot part and retractable thereinto, and a preloaded spring in the body recess normally urging the brush assembly with its wire brush into outward projection from the pilot part of the tool body.

This invention relates to gasket seat cleaning tools in general, and to tools for cleaning gasket-seating grooves in vehicular air couplings in particular.

The present invention is concerned with tools used especially, though not exclusively, in cleaning the annular gasket-seating grooves in vehicular air couplings such as are used between a trailer truck and cab, for example. The tools commonly used to this end are any of a variety of handy tools, such as screwdrivers or files which by some mechanics are bent so as more easily to reach into the gasket-seating grooves and clean them. These grooves are cleaned by scraping their sides, and especially their bottoms where under the relatively high operational air pressures dirt and other foreign matter accumulates and in time cakes into a fairly hard crust. Scraping such grooves in this fashion will fairly clean the grooves only after prolonged and largely blind scraping, for it is impossible to view more than the open top of the groove, and the mechanic will know that the groove is clean only when his sense of touch tells him that the scraping tool he manipulates no longer meets with any unevenness and glides on the groove walls with that characteristic smoothness which the mechanic associates with a clean groove. The task involved in cleaning such grooves is, therefore, time-consuming in any event, and also requires some measure of dexterity which some mechanics either lack or fail to exercise in which case the groove walls are not restored to their smooth finish and a new inserted gasket in the groove may buckle in consequence and cause air leakage when the coupling is connected and subjected to compressed air.

There have also become known some special tools for the purpose of cleaning such grooves. These special tools have in common a handle with a radially movable cutter or cutters which on projection into a groove are turned to cut the latter clean. However, these special tools have never found favor with mechanics, and insofar as is known none of these tools are being used, the apparent reason being that the cutters either fail at times to remove harder crusted matter, or if removing all such matter will at times cut into the groove itself and thereby provide a leakage path.

It is among the objects of the present invention to provide for cleaning the annular gasket groove in standard coupling parts a tool of a type having a body removably insertable into a coupling part for rotary support therein and carrying a radially movable scraper projectible into and from the gasket groove, and when projecting into this groove being self-forming into substantial form-fit therewith and engaging the groove walls with adequate force

2

reliably to clean the groove down to its bare walls on turning the tool body by manipulation of a part thereof outside the coupling part.

It is another object of the present invention to provide 5 a tool of this type in which the scraper is in the form of a wire brush which by a spring is normally projected radially outwardly on the body. With this arrangement, the wire brush is advantageously dimensioned for ready projection into a gasket groove, and the inherent characteristic of a wire brush to respond to longitudinal compression in lateral outward bulging of its wire bristles is made advantageous use of in compelling the wire brush into substantial form-fit with all walls of the gasket groove on subjection to the force of the spring which 15 puts the brush in the groove under longitudinal compression. Further, the spring may be fairly powerful to insure that the substantially form-fitting wire brush in the groove will reliably clean the latter completely on a few turns of the tool and, hence, in a very short time.

20 Further objects and advantages will appear to those skilled in the art from the following, considered in conjunction with the accompanying drawings.

In the accompanying drawings, in which certain modes of carrying out the present invention are shown for illustrative purposes:

FIG. 1 is a fragmentary section through a coupling part having a gasket seated in an annular groove;

FIG. 2 is a side view of a tool which embodies the present invention, with the tool being shown inserted in 30 the same coupling part ready for cleaning the annular groove therein preparatory to reception of a new gasket;

FIG. 3 is a front view of the tool;

FIG. 4 is a rear view of the tool; and

FIG. 5 is a section through the tool taken on the line 35 5—5 of FIG. 3.

Referring to the drawings, and more particularly to FIG. 1 thereof, the reference numeral 10 designates one of two companion members of a typical standard air coupling between a trailer truck and cab for operation of conventional air brakes on the trailer truck by the operator in the cab. The coupling part or member 10 has a front face 12 with a stepped cylindrical opening 14 which forms part of an air passage 16 in the coupling member, and provided in the cylindrical opening 14 is the usual annular groove 18 which serves as a seat for the gasket 20. The coupling member 10 may be carried by a cab, in which case its companion coupling member is carried by the trailer truck intended for the cab, with this companion coupling member being quite similar to the coupling member 10 and also carrying a gasket. In connecting the companion coupling members, they are placed front-face to front-face and gasket to gasket whereupon these members are locked together by the usual releasable locking means (not shown) provided on these members for that purpose.

Owing to rather severe operational conditions, including subjection to fairly high operational air pressures, and further due to more or less ready exposure to dirt and other foreign matter as well as to the elements of the gaskets of non-connected coupling members on non-connected cabs and trailer trucks, these gaskets deteriorate in a relatively short time and require replacement with a new gasket. However, hand-in-hand with deterioration of these gaskets goes accumulation of dirt and other foreign matter 55 in their seating grooves in the coupling members, with this accumulated matter usually caking in time into a fairly hard crust. Accordingly, in order to seat a new gasket properly so as to avoid a possible immediate air leakage path around the gasket, it is imperative that the gasket seating grooves in coupling members are cleaned down to their bare walls before new gaskets may be seated 60 therein.

Reference is now had to FIGS. 2 to 5 which show a tool 22 for cleaning the gasket seating grooves 18 in coupling members 10. The tool 22 has for its major components a body 24 and a wire brush assembly 26. The tool body 24 has an axis x and a front pilot part 28 and a rear handle part 30, of which the pilot port 28 is cylindrical, stepped in this instance, for insertion with a sliding fit into, and rotary support in, the cylindrical opening 14 in a coupling member (FIG. 2), while the handle part 30 is also cylindrical but of larger diameter than the pilot part and its outer periphery is preferably knurled for good grasp by a mechanic's hand. The tool body 24 is in its rear also provided with a recess 32 which within the handle part 30 is cylindrical and continues into the pilot part 28, in this instance as a transverse groove 34 (FIGS. 4 and 5).

The wire brush assembly 26 comprises in this instance a wire brush 36 the bristles 38 of which are held in a binding 40, and a brush carrier in the exemplary form of a plunger 42 having a reduced end 44 in which the wire brush is firmly anchored with its binding 40. The wire brush assembly 26 is located in the recess 32 in the tool body 24, with the wire brush 36 extending through an aperture 46 in the tool body to the outside thereof. The brush assembly 26 is guided in the tool body 24 for movement radially of the axis x. To this end, there is mounted in the tool body 24 a bracket 48 having a guide slot 50 in which is slidably received a peripherally grooved part 52 of the plunger 42. Further guidance is afforded to the brush assembly by the groove part 34 of the recess 32 in the tool body in which the reduced end 44 of the plunger 42 is received with a sliding fit.

The wire brush assembly 26 is normally urged by a spring 60 into the operative position in FIG. 5 in which the bristles 38 of the wire brush 36 project outwardly from the pilot part 28 of the tool body to the maximum permissible extent as determined by engagement of the plunger 42 with the endwall 62 of the guide slot 50 in the bracket 48. The spring 60 is in this instance anchored on a post 64 in the tool body 24.

For replacement of a gasket 20 with a new gasket, the old gasket is removed from the coupling member 10, whereupon the annular groove 13 is cleaned. To clean this groove 18, a mechanic will insert the tool 22 with its pilot part 28 into the cylindrical opening 14 in the coupling member 10 while holding the plunger 42 retracted against the force of the spring 60 so as to hold the bristles of the wire brush 36 within the peripheral confines of the pilot part 28. In thus inserting the pilot part 28 of the tool into the coupling member 10 until the face 66 of the handle part 30 bears against the front face 12 of the coupling member, the wire brush 36 will be in alignment with the annular groove 18 in the coupling member and the mechanic may then release the plunger 42 for spring-urged projection of the wire brush into the groove 18. The mechanic will then turn the tool a number of times until the groove is clean and then remove the tool from the coupling member.

The bound wire bristles 38 are preferably bunched rather closely into a brush which is of a cross-sectional size to enter the annular groove 18 in a coupling member with a somewhat loose fit, and is of greater length than the maximum depth of the groove 18. Further, the wire brush 36 in the groove 18 in a coupling member is by the bottom of this groove kept from its maximum permissible outward projection (FIG. 5) so that the spring 60 then puts the wire brush, and hence also its bristles 38, under longitudinal compression under which these bristles tend to bulge outwardly into substantial form-fit with the groove 18. The bristles themselves are formed of preferably rather stiff and only slightly resilient wire. With these preferred bristles, and with the wire

brush arranged as described, a relatively strong spring 60 may be used to spread the brush into engagement substantially with the entire side walls of the groove 18 in a coupling member with sufficient tightness to have a good scraping action on these side walls, and the same strong spring will also force the ends of the wire bristles 38 into firm engagement with the bottom of the groove so that they will have a highly effective scraping action thereon. Thus, in keeping the wire brush 36 and the spring 60 at these preferred parameters, a mechanic needs to turn the tool only for a short time in order assuredly to clean the groove 18 in a coupling member completely.

While it is preferred to provide a spring for normally urging the wire brush 36 into maximum outward projection, it is fully within the purview of the invention to omit this spring and permit the mechanic, while turning the coupling member relative to the tool in this case, to exert on the plunger 42 whatever outward pressure the mechanic may find best for cleaning the groove.

What is claimed is:

1. A tool for cleaning an annular gasket-seating groove in a cylindrical opening in the front face of a coupling part, comprising a body with an axis and a rear end and having a cylindrical front portion about said axis cross-sectionally dimensioned for slide-fit insertion into, and rotary support in, the cylindrical opening in a coupling part, with said body also having in its rear end a recess extending into said cylindrical body portion, and an aperture leading from said recess to the outer periphery of said cylindrical body portion; and a wire brush assembly including wire bristles and being guided in said recess for movement substantially radially with respect to said axis, with said assembly being movable with said bristles in said aperture into and from outward projection from said cylindrical body portion, and said assembly being accessible at the rear end of said body for manual movement.

2. A tool as in claim 1, which further provides a pre-loaded spring in said recess for normally urging said assembly with said bristles into outward projection from said cylindrical body portion.

3. A tool as in claim 1, in which said wire bristles are bunched for insertion into the annular groove in a coupling part with a substantially loose fit.

4. A tool as in claim 3, in which said assembly is moveable with said wire bristles into further outward projection from said cylindrical body portion than it could in full projection into the annular groove in a coupling part, so that on movement of said assembly with said bristles into full projection into the annular groove in a coupling part with a force to compress said wire bristles longitudinally the latter will be forced into substantial form-fit with the annular groove.

5. A tool as in claim 4, which further provides in said recess a stop engaged by said assembly in said further outward projection of said wire bristles from said cylindrical body portion, and a preloaded spring in said recess normally urging said assembly into engagement with said stop.
